UNITED STATES PATENT OFFICE.

CHAUNCEY W. ABBOTT, OF PITTSBURGH, PENNSYLVANIA, ASSIGNOR TO THE AMERICAN CONDUIT MANUFACTURING COMPANY, OF PITTSBURGH, PENNSYLVANIA, A CORPORATION OF PENNSYLVANIA.

DESIGN FOR A NINETY-DEGREE FLAT ELBOW-COVER FOR FITTINGS FOR ELECTRICAL CONDUITS.

49,693.

Specification for Design.

Patented Sept. 26, 1916.

Application filed August 11, 1915. Serial No. 45,062. Term of patent 14 years.

To all whom it may concern:

Be it known that I, CHAUNCEY W. ABBOTT, a citizen of the United States, residing at Pittsburgh, in the county of Allegheny and State of Pennsylvania, have invented a new, original, and ornamental Design for Ninety-Degree Flat Elbow-Covers for Fittings for Electrical Conduits, of which the following is a specification, reference being had to the accompanying drawing, forming part thereof.

In the drawings, Figure 1 is a bottom plan view, and Fig. 2 is a side elevation

from the left in Fig. 1, illustrating an end view of one leg and a side view of the other leg of a ninety degree flat elbow cover for fittings for electrical conduits, showing my new design.

I claim:

The ornamental design for a ninety degree flat elbow cover for fittings for electrical conduits, as shown.

CHAUNCEY W. ABBOTT.
